OXYGEN FLOW REGULATOR

John P. Strange, Wilkinsburg, Pa., assignor to
Mine Safety Appliances Company, Pittsburgh,
Pa., a corporation of Pennsylvania

Application October 6, 1942, Serial No. 460,957

4 Claims. (Cl. 137—153)

This invention relates to breathing apparatus, and more particularly to a regulator for controlling the flow of compressed oxygen to the user, such as an aviator flying at high altitudes.

It is among the objects of this invention to provide an oxygen flow regulator which reduces high pressure oxygen to a usable pressure, which delivers the oxygen only during inhalation and then with a minimum of effort by the user, and which mixes a variable quantity of air with the oxygen, depending upon the altitude at which the apparatus is used.

In accordance with this invention, a main valve is mounted in a breathing line between a source of oxygen under pressure and the person who is to breathe it. The valve is normally maintained closed by fluid pressure operated means, such as a Bourdon tube, bellows, or the like, actuated by the oxygen under pressure with which it is in communication. The fluid pressure operated means has an outlet which is normally closed by a pilot valve. The act of inhalation by the wearer of the breathing apparatus causes a diaphragm or other suitable device to open the pilot valve and thus release the oxygen pressure from the pressure operated means so that the main valve can open and allow oxygen to be supplied to the user. As soon as he exhales, the pilot valve closes and the oxygen pressure on the fluid pressure operated means increases to cause the latter to again close the main valve. Thus, the oxygen pressure does the work of opening and closing the main valve. Before the oxygen reaches the user, it preferably passes through a device in which it mixes with air that it draws in through a passage controlled by an aneroid valve so that at high altitudes less air will be mixed with the oxygen.

The preferred embodiment of this invention is illustrated in the accompanying drawing in which Fig. 1 is a plan view of my flow regulator with the diaphragm removed in order to show the interior of the device, and Fig. 2 is a side view of the regulator partly broken away to show some of the elements in section.

Referring to the drawing, a cylindrical housing 1 is provided at one side with a threaded outlet nipple 2 to which the inhalation tube 3 of breathing apparatus is connected. The other end of the tube is connected to the face piece worn by the user, referred to herein as an aviator. Mounted in the opposite side of the housing and extending cut through it is a main valve 4 which is connected by a supply pipe 5 to a source of oxygen under high pressure, such as an oxygen

bottle or tank (not shown). This valve has a central inlet passage 7 extending from the oxygen supply pipe to a chamber 8 in the valve. Extending out from this chamber at one side of the inlet passage is an outlet passage 9 that is connected to an outlet pipe 10. The other end of this pipe is connected through means described later to the inside of housing 1 so that when the valve is open, oxygen flows through it and pipe 10 into the housing and then out through nipple 2 to the aviator.

If the valve were always open, oxygen would be delivered during exhalation as well as inhalation, and thus wasted. Accordingly, it is a feature of this invention that the valve is closed automatically during exhalation. In order to close the valve, a valve plug 12 is slidably mounted in the wall of the valve chamber opposite to the inner end of its inlet passage. The inner end of this plug carries a rubber insert 13 for seating against the end of the passage to thereby shut off the valve. The valve normally is maintained closed by means of fluid pressure operated means, such as a Bourdon tube 15 that is rigidly mounted at one end near the side of the housing with its interior in communication with a coupling 16 extending through the housing wall. The outer end of this coupling is connected to a small pipe 17 the opposite end of which is connected to valve 4 outside of the housing. The valve at that point is provided with a transverse passage 18 (Fig. 1) that connects the pipe with the inlet passage 7 of the valve. The Bourdon tube is thus continuously in communication with the supply of high pressure oxygen which tends to straighten or expand the tube. The free end of the tube is pivotally connected by a short link 20 to one end of a lever 21 the opposite end of which is pivotally connected at 22 to the back wall of the housing. Valve plug 12 is bifurcated for receiving the intermediate portion of the lever which has a slot through which extends a pin 23 that pivotally connects the lever to the valve plug. When the Bourdon tube expands, it swings the free end of the lever to the left to the full line position shown in Fig. 1 and thus moves the valve plug inwardly to close the valve.

For the purpose of permitting the Bourdon tube to contract so that the main valve can open during inhalation, the anchored end of the tube is provided with an outlet that normally is closed by a pilot valve 26. The pilot valve includes a lever 27 that is pivotally mounted on a post 28 projecting from the back wall of the housing. A spring 29 connected to the lever normally holds

the valve closed as shown. The opposite end of the lever carries a roller 30. When the pilot valve is opened, the oxygen in the Bourdon tube escapes faster than oxygen can enter the tube through the small pipe 17 from the source of supply, so the tube contracts. This result may be accomplished by using a very small pipe, or by placing in the pipe a restriction 31, as shown in Fig. 2, provided with an opening that is smaller than the pilot valve opening.

As shown in Fig. 1, the outlet pipe 10 from main valve 4 is connected to an aspirating nozzle 36 in the outer end of a transverse passage 37 through a cylindrical casing 38 that is mounted in a recess in the wall of the housing. Thus the casing is located partly inside and partly outside of the housing. The inner end of passage 37 opens into the housing, and its central portion communicates with the hollow interior of the casing which has an air inlet 39 at its exposed outer end, as shown in Fig. 2. This inlet normally is closed by a disc 41 pressed outwardly by a spring 42 carried on a cross bar 43 extending across the inside of the casing. Oxygen injected through nozzle 36 creates a great enough suction to overcome the resistance of spring 42 and thus draws air in through the casing and delivers it mixed with the oxygen to the inside of the housing from which it is withdrawn through the breathing tube 3 during inhalation. To reduce the amount of air drawn in at higher altitudes, the casing contains an aneroid valve 44 of conventional form.

In order to operate the pilot valve, the open side of the housing is sealed by a flexible diaphragm 51 (Fig. 2) mounted in a ring 52 screwed into the housing. The central portion of the diaphragm carries a rigid disc 53 that engages the roller 30 on the pilot valve lever. When the aviator inhales, the diaphragm is sucked inwardly and it thereby depresses the pilot valve lever and opens the pilot valve. This occurs even at low altitudes because spring 42 in casing 38 is strong enough to keep air inlet 39 closed until diaphragm 51 has opened the pilot valve. Opening of the pilot valve releases the oxygen pressure from inside the Bourdon tube which thereupon starts to contract and open the main valve. Opening of the main valve decreases the pressure in the restricted pipe 17 so that the Bourdon tube contracts further and permits a greater flow of oxygen through pipe 10 into the housing. The pressure of the oxygen in the main valve against valve plug 12 also helps to open that valve. As soon as the wearer exhales, the diaphragm 51 is forced outwardly and the pilot valve is closed by its spring 28. Pressure immediately starts to build up in the Bourdon tube which begins to expand and thus close the main valve. Closing of the main valve increases the pressure in pipe 17 so that the pressure likewise is increased in the Bourdon tube to completely close the valve. The force developed by the Bourdon tube and multiplied by the leverage system by which it is connected to the valve plug 12 is sufficient to hold the main valve closed until the aviator inhales again.

It will be seen that the small force developed by inhalation acts on a diaphragm to open the pilot valve. The opening in the pilot valve is so small that only a small force is required to control it. Most of the work of opening and closing the main valve is done by the pressure of the oxygen itself, so the breathing resistance of this flow regulator is very small.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

10. 1. A flow regulator through which oxygen is supplied to the wearer of breathing apparatus, said regulator comprising a main valve adapted to be connected to a source of oxygen under pressure, a Bourdon tube anchored at one end, means operatively connecting the other end of the tube with said valve, a conduit adapted to connect said oxygen under pressure with said tube whereby to expand the tube and thereby normally maintain said valve closed, a normally closed pilot valve associated with said tube, and means adapted to be actuated by the inhalation of said wearer for opening the pilot valve to release the oxygen pressure from said tube whereby the tube contracts and the main valve is opened.
15. 2. A flow regulator through which oxygen is supplied to the wearer of breathing apparatus, said regulator comprising a housing provided with an open side and with an outlet for a gas to be breathed by said wearer, a flexible diaphragm closing said open side and adapted to be drawn inwardly when the wearer inhales through said outlet, a main valve carried by the housing and adapted to be connected to a source of oxygen under pressure and having an outlet connected to the inside of the housing, a Bourdon tube anchored at one end in the housing, lever means operatively connecting the opposite end of the tube to said valve, a conduit connecting the inlet side of the valve with said tube whereby to expand the tube and to thereby normally maintain said valve closed, a normally closed pilot valve mounted in the housing in communication with said tube, and means in the housing operatively connecting said diaphragm with the pilot valve so that when the diaphragm is drawn inwardly it opens the pilot valve and releases the oxygen pressure from said tube whereby the main valve is opened.
20. 3. A flow regulator through which oxygen is supplied to the wearer of breathing apparatus, said regulator comprising a housing provided with an open side and with an outlet for a gas to be breathed by said wearer, a flexible diaphragm closing said open side and adapted to be drawn inwardly when the wearer inhales through said outlet, a main valve carried by the housing and adapted to be connected to a source of oxygen under pressure and having an outlet connected to the inside of the housing, said valve including a slidably closure member, a Bourdon tube anchored at one end in the housing, lever means operatively connecting the free end of the tube with said closure member, a restricted conduit connecting the inlet side of the valve with said tube whereby to expand the tube and thereby normally maintain said valve closed, a normally closed pilot valve for said tube mounted in the housing, and means in the housing operatively connecting said diaphragm with the pilot valve so that when the diaphragm is drawn inwardly it opens the pilot valve and releases the oxygen pressure from said tube whereby the main valve is opened.
25. 4. A flow regulator through which oxygen is supplied to the wearer of breathing apparatus,

said regulator comprising a main valve adapted to be connected to a source of oxygen under pressure, a Bourdon tube anchored at one end, means operatively connecting the other end of the tube with said valve, a conduit adapted to connect said oxygen under pressure with said tube whereby to expand the tube for normally maintaining said valve closed, a pilot valve connected to said tube, a spring pressed lever nor-

5 mally holding said valve closed, and a flexible diaphragm having a rigid central portion for operatively engaging said lever, said diaphragm being adapted to be flexed by the inhalation of said wearer to thereby open the pilot valve to release the oxygen pressure from said tube whereby the main valve is opened.

JOHN P. STRANGE.
